D19680

UNITED STATES PATENT OFFICE.

WILLIAM W. GOODWIN, OF BORDENTOWN, NEW JERSEY.

DESIGN FOR A GAS-RANGE.

SPECIFICATION forming part of Design No. 19,680, dated March 4, 1890.

Application filed January 31, 1890. Serial No. 338,786. Term of patent 7 years.

To all whom it may concern:

Be it known that I, WILLIAM W. GOODWIN, a citizen of the United States, residing at Bordentown, Burlington county, State of New Jersey, have invented a certain new and original Design for Gas-Ranges, of which the following is a full, clear, and exact description, reference being had to the accompanying drawing, forming a part of this specification.

10 My invention relates to gas-ranges; and it consists of the novel configuration thereof in its several parts, as shown in the accompanying photograph, forming a part of this specification.

15 The principal features thereof are an up-

right frame containing a lower chamber closed by two doors, above that two or more laterally-contiguous chambers, with an outwardly-extending shelf at the base thereof, and above that two contiguous open chambers.

I claim—

The design for a gas-range, substantially as shown and described.

In testimony whereof I have hereunto affixed my signature this 5th day of December, 25 A. D. 1889.

WILLIAM W. GOODWIN.
